PORTABLE SANDER

George L. Duff, Long Beach, Calif.

Application August 13, 1945, Serial No. 610,585

6 Claims. (Cl. 51—170)

1

My invention relates broadly to sanding and polishing machines and more particularly to power-operated portable sanding machines of the hand-propelled type.

Such machines are now commonly in use and it is the endeavor of manufacturers thereof to eliminate unnecessary vibration and to screen the moving parts and the power mechanism from the dust and grit which results from their operation. In dealing with the problem of vibration, it is desirable to have the reciprocating or oscillating parts as light as possible in proportion to the weight of the driving parts. By reducing friction, which also causes vibration and increases power consumption, it is possible to use driven parts of less weight as the stresses upon them are reduced. The elimination of large lubricated bearing surfaces reduces friction and also assists in the problem of dust control, focusing it upon the protection of the driving parts.

It is therefore a principal object of my invention to provide a sanding machine having its parts connecting the driving and driven mechanism constructed simply and effectively and combining in themselves efficient anti-friction devices.

It is a further object of my invention to provide a machine in which the connecting bearing surfaces will be self-screening from dust.

Still another object is to provide a machine of few reciprocating parts and those parts of simple construction and light weight.

A further object is to provide a sanding machine having means for selectively adjusting the frequency of vibration in proportion to the resistances developed by the roughness of the surface worked upon and the coarseness of the abrasive utilized.

These and other apparent objects I attain in a manner which will be clear from consideration of the following description taken in connection with the accompanying drawings, of which:

Figure 1 is a perspective view of the sanding machine of my invention showing the assembly of the exterior parts;

Figure 2 is a vertical section along the line 2—2 of Fig. 1;

Figure 3 is a vertical section at right angles to the view of Fig. 2 and taken along the line 3—3 thereof;

Figure 4 is a horizontal section on the line 4—4 of Fig. 3, with parts shown in plan to illustrate exterior and interior assembly;

Figure 5 is a fragmentary section on line 5—5

2

of Fig. 4 illustrating the mounting of the eccentric drive mechanism; and

Figure 6 is another fragmentary section on line 6—6 of Fig. 4, showing the mounting of the bearing mechanism.

Considering now the aforesaid drawings in detail, I have designated by the numeral 10 a housing unit which may be cast in one piece and which comprises a hollow motor housing 11, a handle 12, and a base 13. The motor housing 11 houses a motor 14, access to which is obtained through an opening 15, normally closed by a cover plate 16, which may be held in place by screws 17. The handle 12 has an interior chamber 18 in which is housed a switch 19, the electrical conduits for which emerge to the motor through a passage 20 and to a source of power through a passage 21. The switch 19 is operated by a trigger 22 extending through an opening 23 on the inside of the handle 12, and access to the switch is provided through an opening 24 on the outside of the handle normally closed by a cover plate 25. The base 13 has an opening 26 for receiving the motor during assembly, and a second opening 27 below the handle 12 for access to the parts carried therebelow and closed with a cover plate 28 held by spring flanges 29 to aid its ready removal and replacement. The lateral margins of the base 13 are rabbeted on their lower edges to form recesses 30 for holding members of the hereinafter described bearing mechanism.

A plate 31 of slightly greater length than the housing unit 10, and of the same width, extends 35 therebeneath. On the upper side of the plate 31 are lateral ribs 32 and end ribs 33 forming an open-topped box, the end ribs 33 having outwardly turned flanges 34. The plate has longitudinal extensions 35 beyond the end ribs 33, and lateral extensions beyond the lateral ribs 32 terminating in upturned flanges 36. Clamping bars 37 are mounted in the recesses formed at each end of the plate 31 by the extensions 35 and the flanges 34, being held therein by bolts or screws 38. A sheet of sand paper or buffing cloth 39 may be stretched across the bottom of the plate 31 with its ends turned under the clamping bars 37 and securely held thereby.

To move the plate 31 relatively to the housing unit 10, I provide an eccentric 40 mounted on the motor shaft 41, and held thereto by a set-screw 42. A pitman 43 engages the eccentric 40 with ball-bearings 44, held in place and protected against dust by a cover plate 45. The other end of the pitman 43 engages a pin 46

which is formed integrally with a plate 47 and extends therethrough into a boss 48 on the plate 31. The plate 47 is further held in rigid engagement with the boss 48 by a screw 49.

To support the motor 14 within the motor housing 11 and to protect the motor from dust, I provide a support plate 50 held in place against the motor housing 11 by screws 51, and thickened centrally to provide a bearing 52 for the motor shaft 41. The bearing may be provided with anti-friction devices if desired.

The action of the eccentric 40 and the pitman 43 will cause the plate 31 to have reciprocating motion with respect to the unit 10. To connect the unit 10 to the plate 31 with guide surfaces of low friction I provide ball-bearings of rectilinear type, the races of which are so positioned that the balls act as the connecting means between the unit 10 and the plate 31 in addition to their function of absorbing pressure between these parts. Bars 53 are attached to the housing unit 10 in the recesses 38 by means of screws 54, fitting snugly within the recesses, the ends of which fit around the ends of the bars. A portion of each of the bars 53 extends downwardly below the respective recess 38 and has a longitudinal groove 55 on its inner face. Similar bars 56 are held by screws 57 to the lateral ribs 32 of the plate 31 with grooves 58 in their outer sides and co-extensive with the grooves 55. Both sets of bars 53 and 56 are shorter than the lateral ribs 32 by an amount slightly greater than the length of travel of the plate 31 as caused by the eccentric 40, so that the movement of the plate 31 relative to the unit 10 does not bring the end ribs 33 into contact with the bars 53. The end ribs 33 extend outwardly to the edge of the plate 31 to form enclosures within which the relative movement of the bars 53 and 56 may take place. The upturned flanges 36 complete the enclosures and serve as dustguards.

When the unit 10 is placed upon the plate 31 it will, but for the bearings now to be described, rest upon the upturned flanges 36, with the grooves 55 and 58 not quite in horizontal alignment and cooperating to form channels between them. In these channels I provide bearings comprising a plurality of balls 59 separated by rollers 60. The balls 59 are of slightly larger diameter than the rollers 60, so that the latter sustain no weight but serve as separators only, resting in the bottom of the channels formed by the grooves. The screws 57 holding the ends of the bars 56 are longer than the intermediate screws and extend into the channels where they act as stops to limit the endwise travel of the balls and rollers and to prevent the entry of dust into the channels.

The diameter of the balls 59 is sufficient to hold the inner faces of the bars 53 from the outer faces of the bars 56 and also to hold the bars 53 from contact with the upturned flanges 36. The weight of the unit 10 rests upon the contact points of the upper sides of the grooves 55 with the balls 59, and through the balls to the lower sides of the grooves 58. The same series of contact points prevents lifting the unit 10 from the plate 31 without first removing at least one of the bars 53. In assembling the machine, the unit 10 is placed upon the plate 31, with the bars 56 in place on the latter, and the balls and rollers are then laid in the grooves of the bars 53 which are then fastened in place. The only openings for dust into the channels containing the balls are at the ends of the channels which are pro-

tected by the ends of the end ribs 33 and by the screws 51, and the narrow slots between the bars, the upper of which leads only into the enclosure between the unit 10 and the plate 31 and the lower of which leads into the enclosures formed by the upturned flanges 36.

In reducing vibration and in saving power which is wasted by vibration it is useful to proportion the frequency of reciprocation to the load resulting from the roughness of the surface worked upon and the coarseness of the abrasive sheet 39. To achieve this end I utilize a motor 14 of the variable speed type having a rheostat control 61 at its upper end accessible when the cover plate 18 is removed. Turning the control 61 to adjust it is accomplished by means of a disc 62 which is keyed to the control as shown at 63 and has a screw-driver slot 64 in its upper face. By providing the disc 62 with an annular shoulder 65 which fits against a similar shoulder in the motor housing 11, rigidity of the motor between the support plate 50 and the housing 11 is also secured.

In the operation of the sanding machine, the motor is started by pressure on the trigger 22 of the switch 19. Rotation of the eccentric 40 within the pitman 43 imparts a crank motion to the pitman which in turn imparts a reciprocating motion to the plate 31 and the abrasive sheet 39 attached thereto. When the machine is held against work to be smoothed, the upper element comprising the motor and the housing and handle remains relatively motionless while the lower element comprising the plate and abrasive sheet is moved rapidly back and forth. The only connecting parts between the two elements are the balls 59 and the pitman 43 which is mounted in ball-bearings 44. All stresses, due either to vibration or to reciprocation, are transmitted through balls, the rolling movement of which minimizes friction and vibration and passes only the stresses of reciprocation. With the undesirable stresses minimized, the operator may adjust the rheostat control 61 so as to provide power to turn the motor at that speed which most effectively deals with the remainder having regard to the roughness of the work, the coarseness of the abrasive, and the pressure which the operator wishes to apply.

Having now described and shown my preferred form of invention, I wish it to be understood that I do not mean to be limited to the particular form or arrangement of parts herein described and shown, which is merely illustrative of the broad principles of my invention as defined in the appended claims.

I claim:

1. In a sanding machine having an upper element, and a lower element adapted to have endwise reciprocating motion with respect thereto, bars carried on the sides of each of said elements, the bars carried by the upper of said elements being outside of and in horizontal alignment with the bars carried by the lower of said elements to form cooperating pairs therewith, the adjacent faces of the bars of each of said pairs having grooves cooperating to form channels parallel to the direction of reciprocation, balls carried in each of said channels of sufficient diameter to hold said paired bars apart and to provide support between the lower surface of the groove of any of said bars and the upper surface of the groove of the cooperating bar, end portions on said lower element extending beyond and outwardly around the ends of said bars, and up-

wardly extending flanges on the lower element, said end portions and said flanges being free of contact with said bars but closely cooperating therewith to form a relatively dustproof enclosure.

2. In a sanding machine having an upper element, and a lower element adapted to have end-wise reciprocating motion with respect thereto, bars carried on the sides of each of said elements, the bars carried by the upper of said elements being outside of and in horizontal alignment with the bars carried by the lower of said elements to form cooperating pairs therewith, the adjacent faces of the bars of each of said pairs having grooves cooperating to form channels parallel to the direction of reciprocation, balls carried in each of said channels of sufficient diameter to hold said paired bars apart and to provide support between the lower surface of the groove of any of said bars and the upper surface of the groove of the cooperating bar, end portions on said lower element extending beyond and outwardly around the ends of said bars, and upwardly extending flanges on the said lower element, said end portions and said flanges being free of contact with said bars but closely cooperating therewith to form a relatively dust-proof enclosure, and means within said channels closing the ends thereof against the exit of the said balls therefrom and the entrance of dust thereto.

3. In a sanding machine having an upper power element and a lower element adapted to have end-wise reciprocating motion with respect thereto, the combination of: bars carried by said elements arranged in side-by-side pairs and grooved in their adjacent faces to form a channel between the bars in each of said pairs, one bar of each of said pairs being secured to one of said elements and the other bar in said pair being secured to the other of said elements; balls in said channel of sufficient diameter to hold said paired bars apart and form a rectilinear ball-bearing support for said power element; and end portions and vertically extending flanges on one of said elements, said end portions and flanges being free of contact with said bars, but closely cooperating therewith to form a relatively dust-proof enclosure.

4. In a sanding machine having an upper power element and a lower element adapted to have end-wise reciprocating motion with respect thereto, the combination of: bars carried by said elements arranged in side-by-side pairs and grooved in their adjacent faces to form a channel between the bars in each of said pairs, one bar of each of said pairs being secured to one of said elements and the other bar in said pair being secured to the other of said elements; balls in said channel of sufficient diameter to hold said paired bars apart and form a rectilinear ball-bearing support for said power element; end portions and vertically extending flanges on one of said elements, said end portions and flanges being free of contact with said bars, but closely cooperating therewith to form a relatively dust-proof enclosure; a rotary power shaft extending from said upper element downwardly into said enclosure; an eccentric fixed on said shaft and positioned below a

plane defined by said bars; and a connecting rod connected between said eccentric and said lower elements whereby to drive said lower element in reciprocating motion with respect to said upper element.

5. In a sanding machine having an upper element and a lower element adapted to have end-wise reciprocating motion with respect thereto, the combination of: bars carried on the sides of each of said elements, said bars being arranged in pairs in side-by-side relationship and in horizontal alignment with the adjacent faces of pairs of said bars having grooves therein cooperating to form channels parallel to the direction of reciprocation; balls carried in each of said channels of sufficient diameter to hold said paired bars apart and to provide support between the lower surface of the groove of any of said bars and the upper surface of the groove of the cooperating bar; end portions on said lower element extending beyond and outwardly around the ends of said bars; and upwardly extending flanges on the lower elements, said end portions and said flanges being free of contact with said bars, but closely cooperating therewith to form a relatively dust-proof enclosure.

6. In a sanding machine having an upper element and a lower element adapted to have end-wise reciprocating motion with respect thereto, the combination of: bars carried on the sides of each of said elements, said bars being arranged in pairs in side-by-side relationship and in horizontal alignment with the adjacent faces of pairs of said bars having grooves therein cooperating to form channels parallel to the direction of reciprocation; balls carried in each of said channels of sufficient diameter to hold said paired bars apart and to provide support between the lower surface of the groove of any of said bars and the upper surface of the groove of the cooperating bar; end portions on said lower element extending beyond and outwardly around the ends of said bars; upwardly extending flanges on the lower elements, said end portions and said flanges being free of contact with said bars, but closely cooperating therewith to form a relatively dust-proof enclosure; a rotary power source in said upper element having a shaft extending downwardly into said enclosure; an eccentric fixed on said shaft and positioned below a plane defined by said bars; and a connecting rod connected between said eccentric and said lower element whereby to drive said lower element in reciprocating motion with respect to said upper element.
